UNITED STATES PATENT OFFICE

JOHN D. SEABERT, OF DAYTON, OHIO, ASSIGNOR TO GENERAL MOTORS RADIO CORPORATION, OF DAYTON, OHIO, A CORPORATION OF OHIO

SUPPORT FOR DIAPHRAGM TRANSFORMERS

Application filed June 20, 1931. Serial No. 345,881.

This invention relates to radio apparatus, and particularly to acoustical devices used in connection therewith.

One of the objects of the invention is to simplify the construction of radio loud speakers, or acoustical devices, and this is accomplished by providing an integral member for supporting the diaphragm, the driving mechanism and appertinent elements.

10 A further object of the invention is to provide an acoustical apparatus of compact form, which is accomplished by mounting the contributing elements of the driving mechanism in close relation to one another.

15 A further object of the invention is to conserve space in an acoustical device by mounting the elements thereof in closely coupled relation.

Further objects and advantages of the present invention will be apparent from the following description, reference being had to the accompanying drawings wherein a preferred embodiment of one form of the present invention is clearly shown.

20 In the drawings:

Fig. 1 is a sectional view in part, showing the formation of certain parts contributing to the instant invention, accompanied with a phantom view illustrating the association of the parts mounted thereon.

Fig. 2 is a plan view, illustrating steps in the formation of a blank of material, from which parts contributing to the instant invention are formed.

25 Fig. 3 is a plan view of a modification of the invention.

Fig. 4 is a side elevation of the modified form, substantially as indicated by the arrow 4 in Fig. 3.

30 Fig. 5 is an elevational view, substantially as indicated by the arrow 5 in Fig. 3.

In radio apparatus where there is a considerable amount of mechanism to be mounted within a small and specified space, much difficulty is had with the prior art devices in confining them to the spaces allotted, so that there would be sufficient space left for servicing of the same, or for making connections or alterations, once the mechanism had been 45 completely assembled. This problem has

been solved, by the construction of a supporting member so that the various parts of the mechanism may be assembled in the closest possible relation.

With particular reference to the drawings 55 there is represented in Fig. 2, a formed blank of material 20 from which the diaphragm and driving mechanism supporting member is fashioned. Here the dot-and-dash lines represent the form of the stamping by which 60 the contributing parts of the support is fashioned, while the continuous lines are indicative of the support after formed for use. In practice this blank 20 is struck from a sheet of material so as to include the lines of sever- 65 ance 21, 22, 23, 24 and 25, as well as the mounting apertures 26, 27 and 28, and lead-ways 29 and 29a. This leaves the blank of the configuration disclosed in Fig. 2, the central portion of which is marked off by dot-and-dash 70 lines, and in which there are the apertures 30 and 31 alternately positioned between the radially extending arms 32 and 33 provided by the blanking along the said lines. It will be noted from the illustration that the central 75 portion of the blank or at least the greater portion thereof, is included with or left attached to the free end of the arm 33, thus making this one arm longer than the arms 32 which are substantially of equal length. The 80 arm 33 is also fashioned to include the lateral webs 34 for a purpose that will presently appear.

The blank existing in this form, is next fashioned by extrusion or other method, to 85 form the frusto-conical like supporting member illustrated in solid lines of Figs. 1 and 2, and is accomplished by bending the blank, or dishing it to form the obliquely extending arms there illustrated. To accomplish this, the rim portion 35 is bent along the line as 36 so that the arms 32 and 33 extend obliquely upwardly and inwardly, and thence have their free ends bent outwardly as along the dotted lines 37 and 38 so that attaching portions 39 and 40 lie substantially parallel with the axis of the conical portion of the member. It will be noted that the bend along the line 38 of the arm 33 is substantially at right angles and that this arm is additionally bent 90

as along the line 41 in substantial reverse direction to that of 38, so that in effect there is provided a ledge or table 45 that includes the web portions 34, and is substantially parallel with the base of the conical member.

The supporting member thus fashioned makes provision for the supporting of a diaphragm 50 at its edge or hinge 51, by a clamping ring 52 securing it to the rim 35 of the supporting member in any desired means, as through the agency of screws or bolts through the apertures 28. The diaphragm 50 is of conical form and has its usual spider support 53, and is attached to its moving coil 54 operating in conjunction with the driving motor 55, that is retained within the motor frame 56 as is usual and well known to those skilled in the art. In the formation of the supporting member, the attaching portions 39 and 40 have been disposed in strict concentric relation with the base of the cone and are therefore adapted to receive the motor frame 56 to which they are secured as by spot welding or other desired means, and at the same time centering the motor and diaphragm with respect to the supporting edge 35. The ledge 45 makes provision for mounting a transformer 60, or other separable part of the driving mechanism, and affords an adequate means of securing the parts together in a compact form so that the transformer or like device will be retained substantially within the conical contour of the acoustical device, as is readily seen from the illustration. The transformer 60 is secured to the ledge 45 in any preferred manner as by means of the screws 61 driven into the apertures 27 of the webs 34. Its leads and conductors may be passed through the aperture 29, from where connections are made to the parts 54 and 55, and with an appropriate multiconductor cable by way of the aperture 29a.

With respect to the form illustrated in Figs. 3, 4 and 5, substantially the same principles of construction are observed, though the result is accomplished in a little different manner. The blank 20, as in the preceding form, in a similar manner thereto, is provided with attaching apertures 26, and other apertures as 28 that make for the attachment of the diaphragm 50 to the flange 35 of the supporting member. In forming this member the central portion of the blank is struck outwardly in substantial conical form, to provide the motor supporting legs 65 and 66, each of which are provided with a lateral web 67 and 68 respectively. These elements of the legs 65 and 66 are fashioned from the metal of the blank that would be struck from the center thereof in the fashioning of the said legs, and in each instance the free end of said leg is bent angularly to provide a lug 69 so as to lie in a plane substantially parallel with the base of the

frame member, or of the cone which it supports.

As in the preceding form, the motor is mounted upon the ends of the legs 65 and 66, which in the present instance is accomplished as is illustrated particularly in Figs. 3 and 5. The motor 70 in this instance comprises a substantially flat pole piece 71 that may be secured to the legs in any preferred manner, and preferably aids in supporting a magnet frame 72 which may be accomplished by spot welding or other usual procedure. As is the usual practice in this and other forms of such magnet motors, the field winding is supported in any desired manner, and maintained in cooperable relation with the speaking coil. The lateral extensions 67 and 68 of the motor supporting legs are fully illustrated in Figs. 3 and 5, and make the desired provision for the closely juxtaposed support of the transformer 60, as in the form earlier described. The attaching screws or devices 61 may also support a terminal strip 75 and from which appropriate leads may be made with the several coils of the motor, the transformer, and with the set and power source. In the present instance a portion of the supporting frame 20 is bent outwardly into a lug 76 carrying a grommet 77 that makes for the support and security of a multi-conductor cable. Here, as in the preceding device the operating motor and its transformer are maintained substantially within the conical configuration of the instrumentality, so that when the unit is mounted within a receiver of small dimension, there will be little danger of disturbing the contributing parts and yet the greatest of available space will be reserved for manipulation and adjustment of associated parts of the structure. The connection between the distributing elements of the acoustic device are shortened to a minimum, well protected within the frame structure of the device, and thus not subject to accidental displacement that makes for rupture of the connections and the consequential failure of the unit in its operation.

While the form of embodiment of the present invention as herein disclosed, constitutes a preferred form, it is to be understood that other forms might be adapted, all coming within the scope of the claims which follow.

What is claimed is as follows:

1. In a radio acoustical device, the combination comprising, a diaphragm supporting member of frusto-conical form, said member having a plurality of radially extending arms to support a power plant, one of said arms being deformed to provide a ledge parallel with the base of said cone, said ledge being adapted to support a transformer.

2. A frame for supporting the diaphragm of an acoustic device in proper relation to the driving mechanism of said device, comprising, an annular portion for supporting the

edge of a circular diaphragm, a plurality of arms lying substantially in a frusto-conical shaped surface, said arms being attached to the frame of the driving mechanism so that the diaphragm is held in proper relation with said driving mechanism, and one of said arms providing a ledge to support a transformer in parallelism with the base of said frame.

3. A frame for supporting the diaphragm and driving mechanism of an acoustic device, comprising in combination, an annular portion for supporting the edge of the diaphragm, arms lying substantially in a frusto-conically shaped surface, said arms being attached to the frame of said driving mechanism, and means provided by the arms for supporting a transformer substantially within the conical contour of said acoustical device.

20 4. A frame for supporting a diaphragm and driving mechanism of an acoustical device, comprising in combination, an annular portion for supporting the edge of a conical diaphragm, and arms extending obliquely and disposed outside of said cone for supporting said driving mechanism, said arms providing a platform parallel with the base of said frame for supporting a transformer closely adjacent the driving mechanism, and substantially within the conical configuration of said device.

25 5. A frame for supporting a diaphragm and driving mechanism of an acoustic device, comprising in combination, a member blanked from sheet metal including a plurality of radially extending arms, one of which is of greater length than the others and provides lateral webs integral therewith, said arms being extruded to form a substantially frusto-conical surface, and said one arm fashioned to provide a ledge in parallelism with the base of said member, and the free ends of each arm positioned for attachment to the motor of said driving mechanism, while said ledge and web provide means for supporting a transformer.

In testimony whereof I hereto affix my signature.

JOHN D. SEABERT.
